US0D1089122S

(12) **United States Design Patent** (10) **Patent No.:** **US D1,089,122 S**
(45) **Date of Patent:** **** Aug. 19, 2025**

(54) **XLR CONNECTOR**

(71) Applicant: **Karim Messadek**,
Chanteloup-les-Vignes (FR)

(72) Inventor: **Karim Messadek**,
Chanteloup-les-Vignes (FR)

(**) Term: **15 Years**

(21) Appl. No.: **29/879,038**

(22) Filed: **Jun. 30, 2023**

(51) LOC (15) Cl. **13-03**

(52) U.S. Cl.
USPC **D13/146**

CLAIM

The ornamental design for a XLR connector as shown and described.

DESCRIPTION

FIG. 1 is a perspective view showing the new, original, and ornamental design of a XLR connector;

FIG. 2 is a perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top side plan view thereof; and,

FIG. 8 is a bottom side plan view thereof.

The broken lines in the drawings depict portions of the XLR connector that form no part of the claimed design.

1 Claim, 7 Drawing Sheets
